(57) **CLAIM**

The ornamental design for an unmanned aerial vehicle with multiple propellers, as shown and described.

DESCRIPTION

FIG. 1 is a top plan view of an unmanned aerial vehicle with multiple propellers showing the new design;

FIG. 2 is a bottom plan view thereof;

FIG. 3 is a left side-view thereof;

FIG. 4 is a right side-view thereof;

FIG. 5 is a back plan view thereof;

FIG. 6 is a front plan view thereof;

FIG. 7 is a three-dimensional top perspective view thereof;

FIG. 8 is a three-dimensional bottom perspective view thereof; and,

FIG. 9 is an enlarged view of the portion of the unmanned aerial vehicle with multiple propellers shown in FIG. 1.

1 Claim, 7 Drawing Sheets
